UNITED STATES PATENT OFFICE

2,180,444

COMBUSTION APPARATUS

Ben Valjean, East Lansing, Mich., assignor to
Motor Wheel Corporation, Lansing, Mich., a
corporation of Michigan

Original application July 23, 1934, Serial No.
736,509. Divided and this application Febru-
ary 25, 1937, Serial No. 127,602

5 Claims. (Cl. 158—91)

This invention relates to combustion apparatus of the vaporizing pot type, and more particularly to an improvement in the means for handling the secondary air in apparatus of that character. The present application is a division of my co-pending application Serial No. 736,509, filed July 23, 1934, now Patent No. 2,073,270, granted March 9, 1937, and also relates to the subject matter disclosed in my co-pending application Serial No. 118,867 filed January 2, 1937.

The principal object of the present invention is the provision of means for introducing secondary air in such manner that the relative proportion of secondary air to primary air may be materially reduced, thus eliminating an undesirable excess of air, and thereby effecting a more efficient combustion.

In the drawing—

Figure 1 is a cross-sectional view of a space heater embodying the present invention; and

Figure 2 is a sectional view of the apparatus shown in Figure 1 taken on substantially the line 2—2 of Figure 1.

The space heater illustrated in Figure 1 comprises a combustion chamber 10, a burner 11 enclosed within a jacket 12, and supporting legs 14. The combustion chamber is shown as of cylindrical formation, having a top wall 15 and a flue outlet 16 adjacent its upper extremity. The flue outlet 16 is adapted to be connected to a chimney 17 whereby the draft of the chimney is communicated to the apparatus. An automatic draft regulator 18 is shown associated with the flue outlet 16. The combustion chamber is provided with a door 19 through which access may be had to the interior of the device.

The combustion chamber 10 and the jacket 12 are here shown as being of integral construction. The jacket 12 and combustion chamber are supported by the legs 14 which are attached to the inturned lower edge of the jacket by bolts 25. A burner supporting strap 24 is also secured to the jacket 12 and the legs 14, as clearly shown in Figure 1.

The burner 11 is preferably made up of a cylindrical sheet metal side wall 26, a cast metal bottom wall 27, and a cast metal top wall 28. The top wall 28 is provided with a relatively large central opening 29. The upper and lower extremities of the cylindrical sheet metal portion 26 are preferably cast into the top wall 28 and the bottom wall 27. The burner 11 is in open communication with the combustion chamber 10 through the opening 29 in top wall 28.

The burner 11 is held in operative relation to

the combustion chamber by means of a screw threaded device 30 associated with the support strap 24 and adapted to engage a depression 31 in the bottom wall of the burner. When the screw threaded device 30 is properly adjusted 5 the top wall 28 of the burner 11 is pressed snugly against the shoulder 32 formed at the upper extremity of the jacket 12 and the lower extremity of the combustion chamber 10. An asbestos ring 33 is preferably positioned between the edge of 10 the top wall 28 and the shoulder 32 in order to insure a satisfactory joint.

Air is supplied to the apparatus through two groups of air inlet openings. The sheet metal cylindrical side wall 26 of the burner is provided 15 with five vertically spaced rows of primary air inlet openings 37. These openings are preferably of substantially uniform size and spacing, and as shown, extend over substantially the entire area of the side wall 26. The upper wall 28 20 of the burner 11 projects radially outwardly beyond the side wall 26 of the burner. It is provided with a plurality of uniformly spaced apart openings 38 radially outwardly from the wall 26 and immediately adjacent the inner surface of 25 the side wall of combustion chamber 10. As clearly illustrated in Figures 1 and 2, the primary air inlet openings 37 are relatively much more numerous than the secondary air inlet openings 38. Consequently, the volume of air admitted to 30 the apparatus by the primary air inlet openings is substantially greater than the volume of air admitted to the apparatus by the secondary air inlet openings.

The draft communicated to the apparatus from 35 the chimney 17 causes primary air to be admitted to the burner 11 in a generally horizontal direction, and causes secondary air to be admitted to the combustion chamber in a generally vertical direction. Burner supporting strap 24 does not 40 close the bottom of jacket 12 so that the air of the atmosphere has access to the openings 37 and 38.

Liquid fuel is supplied to the bottom of the burner chamber from a source of supply not 45 shown through a supply pipe 41. A conventional constant level or metering device 42 is associated with supply pipe 41 whereby the quantity of fuel delivered to the apparatus may be regulated.

Baffle means in the form of an annular ring 49 50 having depending radial vanes 50 is mounted upon the top wall 28 of the burner 11. The baffle 49 is preferably formed in two sections as illustrated, to facilitate assembly and removal thereof. A central opening 51 is formed in the baffle 55

which is arranged in alignment with the opening 29 in top wall 28. The opening 51 in baffle ring 49 is concentric with and larger than the opening 29 in top wall 28. The baffle is of such size that 5 the periphery thereof is spaced a slight distance from the combustion chamber 10. As clearly shown, the baffle 49 is arranged above and closely adjacent the secondary air inlet openings 38.

The combustion apparatus illustrated in the 10 accompanying drawing is, as previously mentioned, of the vaporizing pot type. It is an inherent characteristic of such apparatus that the vertical location of the zone of combustion in the apparatus may be varied by regulating the 15 quantity of fuel supplied to the apparatus.

The supply of liquid fuel to the burner 11 through supply pipe 41 can be controlled by suitable adjustment of the metering device 42. When the fuel is first ignited, combustion initially occurs 20 in the lower portion of chamber 11 and will remain in that portion of the chamber so long as but a limited supply of fuel is admitted thereto. As the supply of fuel is increased, visible combustion (flame) rises in the chamber until 25 finally at the maximum fuel feed it is localized wholly within the combustion chamber 10. At this stage of operation all or substantially all of the air admitted through openings 37 is being premixed with the oil vapor in advance of combustion. By suitable adjustment of the metering device 42 of the lower limit of the zone of combustion may be localized in any desired position 30 between the bottom of the burner 11 and the secondary air inlet openings 38 in the combustion chamber 10.

The expression "zone of combustion" is used herein to define the major portion of the flame produced in the apparatus. It should, of course, be understood that there may be intermittent 40 flashes of flame, particularly adjacent the primary air inlet openings 37, outside of what is here termed as the zone of combustion.

In addition to merely supplying air to increase the capacity of the apparatus, the secondary air 45 inlet openings 38 also serve to distribute the flame at the higher stages of operation and cause it to spread out adjacent the side wall of the combustion chamber, thus assuring an efficient transfer of the heat generated to the medium to be heated.

In the vaporizing pot type burners of the prior art it has been thought necessary to introduce secondary air in such a concentrated volume as to definitely fix the highest point at which the lower 55 limit of the zone of combustion may arise. This results in admitting an undesirable excess of air to the apparatus.

According to the present invention this undesirable excess of secondary air has been eliminated, and extinguishment of the fire by reason of the generation of an excess of fuel vapors is avoided by the use of the baffle 49. The baffle is arranged with respect to the secondary air inlet 60 openings 38 whereby to substantially confine a portion of the air entering therethrough in a limited zone and to effectively prevent contact therewith of any great amount of fuel vapors. Thus, at the higher fuel feeds, there is always 65 maintained between the central opening in the baffle 49 and the central opening in top wall 28 a mixture of air and fuel vapors containing a sufficient quantity of air to support combustion. So long as fire is maintained in the apparatus, the 70 possibility of an explosion because of the genera-

tion of an excess of fuel vapors is effectively eliminated.

It is by reason of the particular construction and location of the baffle 49 that it is able to accomplish the function just described. From the 5 drawing it will be noted that the baffle is arranged above the secondary air inlet openings 38 in such manner as to intercept the flow of the air admitted therethrough, reducing its velocity and changing the direction of flow thereof. In other 10 words the air admitted through openings 38 impinges against baffle 49. A portion of the air admitted through the secondary air inlet openings is diverted toward the center of the apparatus where at the higher stages of operation it 15 mixes with the premixture of oil vapors and air delivered to the combustion chamber from the burner through the opening 29 in top wall 28. It also permits a limited portion of the air admitted through secondary air inlet openings 38 20 to travel up the sides of the combustion chamber 10, thus efficiently distributing the flame at the higher stages of operation.

From the foregoing it will be apparent that the essential requirement for preventing extinction 25 of the flame is the provision of means for producing a combustible mixture in the apparatus regardless of the amount of fuel vapors which may be generated. Of course, this mixture must be produced in a region where it will 30 become ignited when the apparatus is operated at maximum fuel consumption. Likewise, it should be so located and of such a nature as not to impair the normal operating efficiency of the apparatus. For example, air should not be introduced for this purpose in such volume as will 35 materially decrease the percentage of CO₂ in the flue gases. Nor should the air provided for this purpose be introduced in a quantity or a direction such as will adversely influence the stability 40 of the combustion process.

The scope of the invention is indicated in the appended claims.

I claim:

1. A burner of the vaporizing pot type comprising a vertically disposed tubular side wall, a centrally apertured horizontal top wall having a periphery extending beyond the side wall, means for delivering liquid fuel to the burner in regulatable quantities to be vaporized in the 45 burner, a plurality of primary air inlet openings formed in the side wall of the burner below the top wall, said primary air inlet openings being proportioned and arranged to introduce air to the burner for premixing without any substantial amount of visible combustion with fuel vapors generated in the burner at certain rates of oil flow to the burner, a plurality of secondary air 50 inlet openings formed in the top wall and adapted to admit air to the apparatus above the top wall outwardly of the side wall, and a centrally apertured baffle ring positioned in spaced relation above the top wall over said secondary air inlet openings, said baffle ring being constructed and arranged to present an obstruction against 55 which the air admitted through said secondary air inlet openings impinges, said baffle having a central opening larger than the aperture in the top wall and having an overall diameter less than the overall diameter of the top wall. 70

2. A burner of the character defined in claim 1, wherein the said primary and secondary air inlet openings constitute the sole means for admitting air to the burner, and wherein the volume of air admitted through the secondary air 75

inlet openings is less than one-half of the total volume of air admitted to the burner.

3. A burner of the vaporizing pot type comprising a side wall, a top wall formed to provide an outlet opening for the burner, means for delivering liquid fuel to the burner in regulatable quantities to be vaporized in the burner, a plurality of primary air inlet openings formed in the side wall of the burner below the top wall, said primary air inlet openings being proportioned and arranged to introduce air to the burner for premixing without any substantial amount of visible combustion with the fuel vapors generated in the burner at certain rates of oil flow to the burner, a plurality of secondary air inlet openings formed in a wall of the burner above the primary air inlet openings and adapted to introduce air to the apparatus above the top wall, and a baffle ring positioned in spaced relation to the top wall above the secondary air inlet openings, said baffle ring having an opening therein larger than the outlet opening in the top wall and arranged in substantial alignment

therewith, said baffle ring and said secondary air inlet openings being constructed and arranged so that the axis of said openings intersect the median horizontal plane of said baffle ring at a substantial angle whereby the baffle presents an obstruction against which the air admitted through said secondary air inlet openings impinges. 5

4. A burner of the character defined in claim 3, wherein said primary and secondary air inlet openings constitute the sole means for admitting air to the burner, and wherein the volume of air admitted through the secondary air inlet openings which impinges against the baffle is substantially less than one-half of all the air admitted to the burner. 10 15

5. A burner of the character defined in claim 3, wherein the baffle ring is also constructed and arranged to direct at least a portion of the air admitted through the secondary air inlet openings toward the outlet opening in the top wall. 20

BEN VALJEAN.
